TOBACCO LEAF STITCHING DEVICE

Edward R. Coley and Sidney L. Coley, Northside, N. C.

Application April 13, 1956, Serial No. 577,966

2 Claims. (Cl. 214—5.5)

This invention relates to an apparatus for stitching tobacco leaves together so as to enable the tobacco leaves to be suspended upon tobacco sticks in a convenient manner for storing and curing.

When curing tobacco it is necessary to suspend them in a loose manner so that the air will have access to all portions of the leaves during drying and curing operations. This suspension is usually effected by attaching leaves to sticks by the use of a string or other means and then the sticks are placed in spaced relation upon supports while the drying and curing operations are in progress. The time and effort involved in the curing operations are considerably reduced by the utilization of the present invention since the large amount of labor usually expended in hand tying the tobacco leaves on the tobacco sticks is substantially eliminated by the use of tobacco leaf stitching devices which automatically accomplishes the tying step.

A further object of the invention resides in the provision of a tobacco leaf stitching device which includes means for conveying a tobacco stick beneath the tobacco leaves to be secured thereon and which includes means synchronized with the conveying means for automatically cutting the end of the thread or string used in stitching the tobacco leaves and for urging the string into suitable clips which may be secured on the tobacco sticks.

Still further objects and features of this invention reside in the provision of a tobacco leaf stitching device that is strong and durable, highly efficient in operation, capable of being utilized in storage or curing barns, on tobacco harvesters, on other mobile vehicles, or on any suitable supporting structure such as a table.

These, together with the various ancillary objects and features of the invention which will become apparent as the following description proceeds, are attained by this tobacco leaf tying device, a preferred embodiment of which has been illustrated in the accompanying drawings, by way of example only, wherein:

Figure 1 is a plan view of the tobacco leaf stitching device comprising the present invention;

Figure 2 is a side elevational view of the apparatus;

Figure 3 is a vertical sectional view of the device as taken along the plane of line 3—3 in Figure 2;

Figure 4 is a sectional detail view specifically illustrating the stitching needle and tobacco leaf guide arrangement as taken along the plane of line 4—4 in Figure 3;

Figure 5 is a horizontal sectional detail view as taken along the plane of line 5—5 in Figure 4;

Figure 6 is a perspective view illustrating the appearance of a plurality of tobacco leaves as secured on a tobacco stick in accordance with the concepts of the present invention;

Figure 7 is a sectional detail view as taken along the plane of line 7—7 in Figure 2 showing in an enlarged scale the construction of the means for automatically cutting the thread or string on the end of a tobacco stick;

Figure 8 is an enlarged sectional detail view illustrating

2

the engagement of the follower and the cam surface on the sprocket for actuating the cutter;

Figure 9 is an elevational detail view of the sprocket with the cam surface engaged by the follower;

5 Figure 10 is a plan view of a modified form of the conveyor arrangement employing a butt board and tray;

Figure 11 is a partial perspective view of the cutter arm and means for holding the string on the end of a tobacco stick;

10 Figure 12 is a sectional detail view of a modified form of cutter adapted to be utilized in the present invention shown with the cutter in an opened position; and

Figure 13 is a view similar to that of Figure 12 but showing the cutter in a closed position.

15 With continuing reference to the accompanying drawings wherein like reference numerals designate similar parts throughout the various views, reference numeral 20 generally designates the tobacco leaf stitching device comprising the present invention. This device may be 20 mounted on a suitable table 22, on a vehicle such as a tobacco harvester or the like, or any convenient place in a barn or like building.

Mounted on a platform as at 24 supported by the table 22 is a drive motor 26 of any suitable type which drives

25 sprocket 28 and the endless belt 30 entrained thereabout. The endless belt 30 is entrained about a sprocket 32 mounted on a shaft 34 on which sprockets 36 and 38 are also mounted. The endless belt 40 is entrained about the sprocket 36 and about a sprocket 42 on shaft 44

30 which has a sprocket 46 positioned thereon about which endless belt 48 is entrained. Entrained about the sprocket 38 is an endless belt 50 which is entrained about the sprocket 52 mounted on a shaft 54 having a similar sprocket 56 secured thereon. Entrained about the 35 sprocket 56 is an endless belt 58 which is entrained about a sprocket 60 carried by the stub shaft 62 affixed to the table 22.

Mounted on the shaft 54 which extends transversely between the two side frame members 62 and 64 of the 40 table 22 are rollers 66 and 68 about which endless belt conveyors 70 and 72 are entrained. Coextensive with the endless belt 70 and 72 are endless chain conveyors 74 and 76 having a plurality of links from which pins as at 78 and 80 extend normal thereto. The conveyors 70

45 and 72 are adapted to receive tobacco leaves thereon with the stems being received between adjacent pins 78 and 80 on the endless chain conveyors 74 and 76.

Operation of the conveyors 70 and 72 on the endless chains 74 and 76 is accomplished by rotation of the shaft 50 54 upon operation of the motor 26.

Positioned between the endless chains 74 and 76 is a tobacco stick conveyor chain 90 coextensive with the conveyors 70 and 72 and entrained about a sprocket 94 carried by the shaft 54. The conveyor chain 90 for the 55 tobacco sticks has a plurality of lugs 96 arranged in spaced relationship along therewith so as to move tobacco sticks with the conveyors 70 and 72. The spacing of the lugs 96 permits timed operation of the device.

The endless belts 70 and 72 as well as the endless 60 chain conveyors 66, 68 and 74 are entrained about rollers and sprockets mounted on a shaft 100 on the other end of the table. Adjacent the shaft 100 and centrally disposed with respect to the table 22 is a magazine 102 for a plurality of tobacco sticks 104 which are successively 65 fed onto the tobacco stick conveyor 90 as the successive lugs 96 on the tobacco stick conveyor 90 engage the lowermost of the tobacco sticks 104 in the magazine.

Mounted on a yoke 103 driven by the endless chain 48 is a shaft 106 carrying a sprocket 108 about which the 70 chain 48 is entrained. The shaft 106 is mounted in bearings as at 110 and carries a sprocket 112 which intermeshes with a larger sprocket 114, see Figures 3 and 4,

mounted on a shaft 116. The shaft 116 carries a pulley 118 about which an endless belt 120 is entrained, the endless belt 120 being also entrained about pulleys 122, 124, and 126 adjustably carried by a guide bar 128 through the use of the adjustable arms 130. These pulleys are comparatively flat and wide and belt 132 is entrained about the pulleys rotatable with the pulleys 122, 124 and 126 so that actuation by the belt 120 will serve to operate the other belt 132 and the pulleys mounted in opposed relationship with respect to the endless belts 70 and 72 on the endless chain conveyors 74 and 76 thus forming a moving guide for tobacco leaves.

Also keyed to the shaft 106 is a disk 140 having an arm 142 eccentrically secured thereto at 144 which arm serves to reciprocate the needle 143 receiving thread 146 from a bobbin 148 or the like. The needle 144 is actuated in timed relationship with respect to the hook 150 mounted on the shaft 152 and driven by means of the endless belt 154 entrained about the sprocket 36 and about a sprocket 156 mounted on the shaft 152. The needle is spaced from stick conveyor 90 and tobacco sticks carried thereby. Driven by the endless chain 58 is a sprocket 160 which intermeshes therewith and which has a cam surface 162 provided therein which is adapted to be engaged by a follower 164 mounted on an arm 166 which is pivotally secured at 168 to a mounting bracket 170 carried by the frame member 62. The arm 166 carries a shank 172 having a blade 174 on the end thereof. This blade is adapted to cut the string or thread 146 in timed relationship with respect to the movement of the tobacco stick along the tobacco stick conveyor 90 due to the relative size relationship of the sprocket 160 and the drive for the endless belt conveyor 90. It is noted that the motion of the cam surface 162 serves to pivot the follower 164 and its associated arm 166 and hence raise the shank 172 and the blade 174.

As can be seen best in Figure 12, a modified form of blade 174 is utilized, the modified blade being indicated at 190 and including a blade portion 192 having another spring pressed pivotally mounted blade portion 194. The blade portion 194 is normally urged into an open position by means of a spring 196 and its open portion is limited by means of a stop 198. However, when the shank 200 to which the blade portion 192 is attached is lowered, the blade 194 will engage a stop 202 mounted on the table 204 and the blade portion 194 will be cammed into cutting engagement with the blade portion 192 in a scissor manner.

A rotating butt cutter 210 may be mounted on the frame member 62 so that the butts or stems of tobacco leaves that are too large or unwieldy may be easily cut in a convenient manner.

As shown best in Figure 10, a tray 214 as well as an enlarged board 216 with spaced pins 218 and 220 respectively may be provided for receiving tobacco leaves thereon of divergent sizes and shapes at some portion of the movement of the belts. These features are, of course, optional.

As can be best seen in Figure 11, the tobacco sticks 104 may be provided with substantially Z-shaped clips 105 on the ends thereof so that when the cutter blades as at 174 cut the end of the strings, the cutter blades will press the end of the strings into the clips 105 in an automatic manner.

The foregoing is considered as illustrative only of the principles of the invention. Further, since numerous

modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A tobacco leaf stitching apparatus comprising a table, a pair of endless belt conveyors supported on said table, a pair of endless chain conveyors coextensive with said endless belt conveyors extending along the adjacent side edges of said endless belt conveyors, drive means for driving said endless belt conveyors and said endless chain conveyors connected thereto, a stitching device supported by said table between said endless chain conveyors for stitching stems of tobacco leaves together, a tobacco stick conveyor between said endless chain conveyors for moving tobacco sticks in synchronization with movement of tobacco leaves by said belt conveyors, said stitching device being in alignment with said tobacco stick conveyor, and means synchronized with said drive means for cutting the thread stitching tobacco leaves together adjacent an end of a tobacco stick on said tobacco stick conveyor, said last recited means including a sprocket driven by said drive means, a cam surface on said sprocket, a pivotally mounted link having a follower appended thereto, said follower engaging said cam surface on said sprocket, a shank attached to said link and having a blade affixed thereto, said blade overlying said tobacco stick conveyor.

2. A tobacco leaf stitching apparatus comprising a pair of endless belt conveyors for supporting and conveying tobacco leaves, a pair of endless chain conveyors coextensive with said endless belt conveyors extending along the adjacent side edges of said endless belt conveyors for engaging and conveying stems of tobacco leaves, a plurality of lugs secured to said endless chain conveyor in spaced relationship, stems of tobacco leaves being receivable between said lugs, drive means for driving said endless belt conveyors and said endless chain conveyors connected thereto, a stitching device between said endless chain conveyors for stitching stems of tobacco leaves with thread joining the stems together, a tobacco stick conveyor between said endless chain conveyors for moving tobacco sticks in synchronization with movement of tobacco leaves by said belt conveyors, said stitching device being in alignment with said tobacco stick conveyor, and means synchronized with said drive means for cutting the thread stitching tobacco leaves together adjacent an end of a tobacco stick on said tobacco stick conveyor, said last recited means including a sprocket driven by said drive means, a cam surface on said sprocket, a pivotally mounted link having a follower appended thereto, said follower engaging said cam surface on said sprocket, a shank attached to said link and having a blade affixed thereto, said blade overlying said tobacco stick conveyor.
